[57] **CLAIM**

The ornamental design for dispenser for liquid air freshener, as shown and described.

DESCRIPTION

FIG. 1 is a side elevational view of a dispenser for liquid air freshener showing my new design, the ornamental pattern being repeated at 120 degrees intervals;

FIG. 2 is another side elevational view thereof showing the dispenser in an open position;

FIG. 3 is a top plan view thereof; and

FIG. 4 is a perspective view taken from the top and one side thereof.

FIG. 4

FIG. 2

FIG. 1

FIG. 3
